(57) CLAIM

The ornamental design for a handle for a toothbrush, as shown and described.

DESCRIPTION

FIG. 1 is a perspective front view of a handle for a toothbrush showing my new design;

FIG. 2 is a front view thereof;

FIG. 3 is a back view thereof;

FIG. 4 is a left side view thereof; and,

FIG. 5 is a right side view thereof.

The broken line schematic showing of the head is for illustrative purposes only and forms no part of the claimed design.
